(57) **CLAIM**

The ornamental design for fluid distribution equipment as shown and described.

DESCRIPTION

Fig. **3.1** is a perspective view of a first embodiment of the fluid distribution equipment;

Fig. **3.2** is a front view thereof;

Fig. **3.3** is a back view thereof;

FIG. **3.4** is a left view thereof;

fig. **3.5** is a right view thereof;

Fig. **3.6** is a top view thereof;

Fig. **3.7** is a bottom view thereof.

Fig. **4.1** is a perspective view of a second embodiment of the fluid distribution equipment;

Fig. **4.2** is a front view thereof;

Fig. **4.3** is a back view thereof;

Fig. **4.4** is a left view thereof;

Fig. **4.5** is a right view thereof;

Fig. **4.6** is a top view thereof;

Fig. **4.7** is a bottom view thereof.

Fig. **5.1** is a perspective view of a third embodiment of the fluid distribution equipment;

Fig. **5.2** is a front view thereof;

Fig. **5.3** is a back view thereof;

Fig. **5.4** is a left view thereof;

Fig. **5.5** is a right view thereof;

Fig. **5.6** is a top view thereof;

Fig. **5.7** is a bottom view thereof.

Fig. **6.1** is a perspective view of a fourth embodiment of the fluid distribution equipment;

Fig. **6.2** is a front view thereof;

Fig. **6.3** is a back view thereof;

Fig. **6.4** is a left view thereof;

Fig. **6.5** is a right view thereof;

Fig. **6.6** is a top view thereof;

Fig. **6.7** is a bottom view thereof.

1 Claim, 28 Drawing Sheets
